UNITED STATES PATENT OFFICE.

JAMES FLEMING LOW, OF TORONTO, ONTARIO, CANADA.

MACHINE FOR MANUFACTURING PULP ARTICLES.

Application filed December 16, 1926. Serial No. 155,306.

This invention relates to a machine for making pulp articles, as described in the present specification and illustrated in the accompanying drawings which form part 5 of the same.

The invention consists essentially of the novel features pointed out broadly and specifically in the claims for novelty following 10 a description containing an explanation in detail of an acceptable form of the invention.

The objects of the invention are to provide a machine of greatly increased efficiency; to build a machine wherein the 15 stock tank moves upwardly to immerse the dies; to allow the water or pulp solvent in the die box to run out by gravity as well as by suction; to have means of agitating the pulp solution in the stock tank; to construct a machine wherein the dies are 20 rotated in one direction only; and generally, to improve on the machines now in use, and to supply a machine very economical of operation and of construction.

25 This machine is one wherein a female and a male die are used, the dies being designed to hold a plurality of laminations formed to correspond to the shape of the finished article. The laminations may be arranged 30 or mounted in any suitable manner, so as to cause the female die to become covered or coated with the pulp substance when the die box enclosing the laminations is submerged into a pulp mixture and vacuum applied to cause the solvent or water to run 35 through or between the laminations. The female die must be first coated with the pulp substance, after which the male die is operated to engage the female die and give the 40 article its finished form; and as will be explained later, the male die also operates to remove or pick the finished pulp article from the female die.

In the drawings, Figure 1 is a side elevation view;

45 Figure 2 is a perspective view of the stock tank;

Figure 3 is a plan view, showing parts broken away and in section for the sake of clearness;

Figure 20 is a fragmentary side elevation 90 view of Figure 19;

Figure 21 is a section taken along line 21—21 of Figure 19;

Figure 22 is an end view of Figure 15.

Like numerals of reference indicate corresponding parts in the various figures.

Referring to the drawings, 10 is the base of the machine mounting the frame 11. 12 is the stock tank having laterally-extending brackets 13 formed to slide in the tracks 100 14 provided in two of the inner faces of the frame 11. The tank is provided with the pivots 17 projecting out from two sides thereof, by means of which it is supported by the eccentric rods 18. The tank is fed by the pipe 23, and a suitable overflow (not shown) is provided in order to keep the level of the pulp solution at any predetermined level according to the size of the dies used. 105

15 is a horizontally-arranged shaft rotat- 110

ably mounted in the frame 11 under the tracks 14 and under the tank 12; the shaft rigidly mounts, adjacent to two sides of said tank, the eccentrics 16. 18 are eccentric rods 5 pivotally mounted between the pivots 17 and the eccentrics 16. As the shaft 15 rotates, the tank 12 moves up and down in the tracks 14.

19 is the drive shaft, suitably journaled 10 in the frame 11 and having the drive pulley 20 rigidly secured thereupon; 21 are two gears rigidly carried by the shaft 19 adjacent two of the outside faces of the frame, and 22 are two gears rigidly carried by the shaft 15 and meshing with the gears 21. The tank is therefore actuated vertically by the rotation of the drive shaft 19.

Each of the gears 22 is slotted to receive a stud or crank pin 25 adapted to be adjustably secured in the slot; 28A are levers, one on each of two sides of the frame, pivoting on the studs 28; 27 are two crank rods each pivotally mounted between the crank pin 25 and the lower end of the lever 28A. The 25 crank rods 27 are preferably slotted at one end, as shown. The gears 22 are slotted in order to regulate the stroke of the crank pins 25, this being necessary when the number of molding dies used in the machine is to be varied. The drawings show the application of four dies, uniformly spaced at 90°, each die being rotated through 90° for each revolution of the shaft 15; if eight dies are to be used, it follows that the studs 25 must 30 be so adjusted in the gears 22 as to cause the dies to rotate through an angle of 45° for every revolution of the shaft 15.

29 are two levers, one on each of two sides of the machine, pivoting at 30; and 31 are 40 two levers rigid or movable with the levers 29, the levers 31 being slotted at 32 to slidably and pivotally engage the pin 32A carried by the upper ends of each of the levers 28A. As the shaft 15 and the gears 22 rotate in the direction of the arrow (Figure 1) 45 the crank pins 25 rotating in the same or anti-clockwise direction), the levers 28A rotate in an anti-clockwise direction, causing the levers 29 and 31 to rotate in a clockwise direction.

35 is a rotatable shaft detachably mounting the four evenly-spaced die brackets 40, 40A, 40B, and 40C; the shaft is made hollow, with reduced plug-like end portions 36 rigid therewith, the reduced ends rotating in the bearings 37 and extending therethrough. Rotatably mounted on and adjacent each end of the reduced shafts 36 is a disc or ratchet plate 37A pivotally carrying the pawl 38 co-acting with a ratchet 39 which is rigidly carried by the reduced end adjacently of said disc 37A. 106 are connecting links each pivotally connected between the disc 37A and the upper end of the lever 29. As the links 60 106 travel towards the shaft 35, the discs

37A rotate in an anti-clockwise direction, causing the pawls 38 to slide over or upon the ratchets 39; and as the links travel away from said shaft, the discs rotate in a clockwise direction, causing the ratchets and the 70 shaft 35 to rotate with said discs owing to the engagement of the pawls with said ratchets. In other words, the shaft 35 and the die brackets mounted thereon are rotated only in a clockwise direction and at regular intervals, the die brackets rotating through an angle of 90° for every revolution of the shaft 15.

60 are a pair of parallel-spaced horizontal rods rigidly secured to the bosses 63 and 64 80 of the extension brackets 56, and each slidably mounting the sliding split bearing 61; 62 is a helical spring encircling each of the rods 60, bearing at one end upon the boss 63 and fitting at the other end in a recess formed 85 in the split bearing 61; the springs are tensioned to normally hold said split bearings against the outer bosses 64.

105 is a hollow shaft of similar construction to shaft 35, having the reduced plug-like end shafts 36 rigid therewith and rotating in the split bearings 61 through which they extend. As the shaft 105 depends upon the split bearings 61 which slide on the horizontally-arranged bars 60, it follows that the shaft 105 is movable in a horizontal plane. The shaft 105 detachably mounts the four evenly-spaced die brackets 108, 108A, 108B, and 108C, lying in a same vertical plane with the die brackets 40, 40A, 40B, and 40C and 100 at right angles to the axis of the shaft 35.

50 are two gears of equal pitch diameter to that of the gears 22, each rotatably mounted on a spindle or stud 51 which projects out from the frame, and being vertically above and meshing with said gears 22; 105 52 is a cam rigid and rotating with each of the gears 50.

53 are substantially L-formed cam levers each pivotally mounted adjacent each of two sides of the frame by means of a stud 54, and each having the roller 55 adapted to operatively engage and ride upon the cam 52. The cam 52 is made to a contour substantially as shown, the cam crank 53 remaining stationary for one half of a revolution of the cam, then uniformly rotating in an anti-clockwise direction for a time equivalent to $\frac{1}{12}$ ths of a revolution of said cam, and then uniformly rotating in a clockwise direction for a time equivalent to $\frac{1}{12}$ th of a revolution of said cam.

55 is a pair of arms each pivotally mounted on a stud 57 carried on one side of the extension brackets 56; 59 is a link of adjustable length pivotally carried by each of the levers 55 and the crank levers 53, whereby any rotation of the levers 55 is transmitted to the levers 55. The upper ends of the levers 55 are slotted to slidably and 130

tatably engage the reduced ends 36 of the shaft 105. It will be seen that the split bearings 61, and therefore the shaft 105 and the die brackets mounted thereon, are moved 5 horizontally against the action of the springs 62 by the oscillation of the levers 55.

Rotatably mounted on and adjacent each end of the reduced shafts 36 of the shaft 105 is a disc or ratchet plate 108 pivotally 10 carrying the pawl 109 co-acting with a ratchet 110 which is rigidly carried by the reduced shaft adjacently of said disc 108. 111 is a connecting link pivotally carried at one end by the lower end of each of the 15 levers 29 and pivotally and slidably carried at the other end by the engagement of the slot 115 with the pin or stud 112 which is rigidly carried by each of the discs 108. As the die brackets on both the shafts 35 and 20 105 must be simultaneously rotated in a same direction and by equal increments of 90°, it follows that the connecting links 106 and 111 must be on opposite sides of a plane passing through the centres of said shafts.

25 As the shaft 105 shifts towards the shaft 35 for a time equivalent to $\frac{1}{12}$ ths of a revolution of the cam 52 while during that time the links 111 move away from said shaft 35, the slots 115 are therefore provided to allow the pins 112 to move unimpeded relatively to said links. Each of the discs 108 is recessed in to receive the lead weight 108A by means of which the disc is rotated in an anti-clockwise direction preparatory to 30 being rotated in a clockwise direction by the action of the links 111.

115 are two circular discs, hereafter named indexing plates having four equally-spaced notches 116A in the periphery thereof, each of said discs being rigidly secured 40 on the reduced end of the shaft 35 between the bearing 37 and the ratchet 39.

116 are two circular discs termed indexing plates, similar to the discs 115 in shape and 45 size, having four equally-spaced notches in the periphery thereof, each of said discs being rigidly secured on the reduced end of the shaft 105 between the split bearing 61 and the ratchet 110.

50 118 are indexing fingers or plungers, each slidably in a fixed bracket 119 and having the collar 120 and the roller 121. 122 are indexing fingers similar to the indexing fingers 118 in shape and size, and having the 55 collar 123 and the roller 124, each of said fingers sliding in the bearing 125A formed in the split bearing 61. 125 are two cam bars, slidably supported on two sides of the frame by the horizontally-arranged brackets

60 126 and 127; the lower edge of each cam bar is notched at 128 and 129 riding on or engaging the rollers 121 and 124 respectively. A spring 130 encircles each of the fingers 118 and is supported at the bottom 65 in the bracket 119 and bears at the top upon

the collar 120, the spring being tensioned to normally urge the finger 118 upwardly.

A spring 131 encircles each of the fingers 122, and is supported at the bottom in the bearing 125A and bears at the top upon the 70 collar 123, the spring being tensioned to normally urge the finger 122 upwardly. 132 are two levers, each pivotally carried by the frame at 94; the lever is slotted at 132A to pivotally and slidably engage the pin 133 75 carried by each of the cam bars 125 and having the lug 133A sized and situated to be slidably engaged by the catch or dog 134 carried by each of the gears 50. The movement of each of the cam bars in one direction 80 is determined by the engagement of the pin 105A with the bracket 127, and a spring 130 mounted as shown, is tensioned to normally hold the pin 105A in engagement with said bracket. The notches in the cam bars are 85 so situated that the rollers normally ride in said notches, so that the fingers normally engage the periphery of the indexing plates or the notches 116A therein.

The catches 134 must be so sized and located that the fingers 118 and 122 will clear the notches in the indexing plates 115 and 116, respectively, just long enough to enable these plates to be rotated through a very 90 small angle. 95

In order to absorb or destroy the momentum of the die brackets on both of the shafts 35 and 105 before their rotation is suddenly checked after each quarter revolution, I provide at both ends of the shafts a leather pad 100 170 held in a metal shoe 171 which fits into a recess in the end of the bearing caps 172A, the brake or pad being adjusted by means of the cap screw 172 threaded in the cap 172A, and in order to better insure the engagement of the indexing fingers with the notches in the indexing plates, the notches are preferably rounded on one side as at 116B.

The die brackets for each of the shafts 35 110 and 105 are made as shown in Figures 19 to 21, having the flat base 42, the curved flange 41 formed to fit upon the shaft to which it is detachably secured, and the four ribs 43 radiating from the central columnar shaped portion 140, the portion 140 and the ribs extending between said base and flange. The base 42 of each bracket is made flat to receive a die box 44 within which are secured the laminations. 115 120

The portion 140 in each die bracket is cored to provide a passage through which is passed a pipe 71, the pipe being threaded at one end to receive the elbow 75 and threaded at the other end to receive the nut 45 which is countersunk or recessed in the base. By screwing the nut 45 upon the pipe, the elbow may be made to bear tightly upon the inside of the shaft upon which the bracket is mounted. A second nut 46 is screwed upon 125 130

the pipe 71 over the nut 45, the bottom of the box being recessed to enclose said second nut. A second pipe 141 is screwed into the elbow 75 and run through one of the reduced 5 ends of each shaft, the outer end of said pipe being threaded to receive the nut 142 which fits in a recess made in the end face 152 of the reduced shaft. The pipes 71 and 141 and the elbow 75 form a line of piping or a continuous 10 passage between the die box and the end face of the reduced shaft; four such lines or passages are provided in each of the shafts 35 and 105, these lines being referred to, in the statement of operation, as the 15 bracket pipe lines.

143 and 144 are cup-shaped castings having the side wall 145 and bottom 146, and fitting over and upon one end of the shafts 35 and 105, respectively. The castings have 20 the two fingers or projections 146A which engage the grooves 147 in the brackets 148 and 148A, the bracket 148 being formed to be bolted to the frame 11 and the bracket 148A being formed to be bolted to the split 25 bearing 61. Each casting when applied and retained on the end of its respective shaft—the function and action of which will be explained in the statement of the operation of the machine—forms a chamber, to be termed 30 hereinafter a "vacuum chamber." The contacting surfaces between each casting and its corresponding shaft are machined to give a sliding fit.

In each chamber is a wax washer or ring 35 150 fitting on a shoulder formed in the periphery of the hollow shaft, and also a second wax washer or disc 151 bearing upon the end face 152 of the reduced shaft; 161, 161A, 161B and 161C are ports or passages 40 through the wax washer 151 and spaced to be in alignment with the pipes 141 when the shafts 35 and 105 are temporarily locked against rotation. 153 is a metal disc held in contact or engagement with the wax washer 45 151 by means of the tensioned springs 154, four equally-spaced recesses 155 being provided in the inner face of said disc 153 to receive the nuts 156. The disc is provided with a number of pins 161 engaging co-acting 50 recesses in the wax washer 151 so as to retain or lock same with its ports in alignment with the pipes 157, 157A, 157B and 157C.

157, 157A, 157B and 157C are four pipes 55 rigidly carried by the disc 153 by means of the nuts 156, and extending out through the chamber wall 146 and loosely mounting said springs 154.

In the wax washer enclosed in the vacuum 60 chamber associated with the shaft 35, are recesses or passages 162 and 163 formed as shown in Figure 4; the recesses 162 operatively connecting the ports 161A and 161B; in the wax washer enclosed in the vacuum 65 chamber associated with the shaft 105, are

recesses or passages 175 and 176 formed as shown in Figure 5.

The pipe 157C of castings 143 and 144, and the pipe 157 of casting 144, are open to the atmosphere; the pipes 157A and 157B 70 of casting 143 are connected to a pipe 166 having the suction pump 167 intermediate of its length; the pipe 157 of casting 143 is connected to the pipe 169 having the vacuum tank 170 and suction pump 171 intermediate of its length, the pipe 169 opening to the atmosphere; the pipe 157B of casting 144 is connected to a pipe 171 having the suction pump 172 intermediate of its length; the pipe 157A of casting 144 is connected 75 to a pipe 173 having the suction pump 174 intermediate of its length. The pipes 166, 171 and 173 all lead to a suitable trap 168 wherein the liquid and air are separated, the water passing out through the pipe 164 and 80 into a tank (not shown), and the air being forced into the pipe 175 and into the perforated pipe 165 carried in the tank 12. By forcing air into the pipe 165, the exhaust from all of the suction pumps can be 85 utilized to agitate the pulp mixture.

In applying vacuum to coat a lamination die with the pulp substance, it is preferable that the liquid mixture be allowed into the die in varying volumes, first in a comparatively small volume and then in an increased volume; accordingly, a suitable valve 169A controlled from the machine, is provided, whereby the liquid is sucked up into or through the laminations in the die (40 in 100 Figure 1) is comparatively small, so as to permit of an initial coat of the pulp substance to be deposited upon the laminations, and then an increased flow turned on to complete the coating to the required thickness. 105

Although it is stated herein that male dies are used for finishing the pulp articles, in articles not requiring a finished appearance, the male dies then are only necessary to remove the articles. 110

But it must be expressly understood that this invention is not limited to or dependent upon the utilization of the exhaust for agitating the pulp solution, since any other agitating means can be employed. It is to be 115 noted that the vertical reciprocating movement of the tank 12 agitates the mixture; but again, the invention is not limited or dependent upon the use of a vertically moving tank.

Operation.—The rotation of the shaft 19 causes the rotation of the gears 21, 22 and 50, the rotation of the gears 22 causing the oscillation of the levers 28A and 29. The oscillation of the levers 29 causes the links 125 106 and 111 to alternately move toward and away from one another. As these links move toward one another, the discs 37A and 108, and therefore the indexing plates 115 and 116 and the shafts 35 and 105, rotate 130

in a clockwise direction through an angle of 90°; as these links move away from one another, the pawls 38 and 109 ride or slip over their respective ratchet wheels 39 and 110, these ratchet wheels remaining stationary. As the rotation of the shafts 35 and 105 depends upon the rotation of the gears 22, it follows that these shafts will be rotated through 90° for every revolution of 10 said gears. Just before the discs 37A and 108 have completed their periodical anti-clockwise rotation of 90°, the dogs 134 engage the lugs 133A of the levers 132, forcing the cam bars 125 to move toward the 15 shaft 35 and causing the indexing fingers 118 and 122 to disengage the notches 116A in the indexing plates 115 and 116, respectively. Before the dogs 134 have travelled sufficiently to disengage the lugs 133A, the 20 indexing plates have rotated sufficiently to clear the notches from the indexing fingers. As soon as the indexing plates, and therefore the shafts 35 and 105 have rotated through an angle of 90°, the indexing fingers 25 will travel upwardly under the action of the springs 130 and 131 to engage the next notches.

For every revolution of the gears 22, therefore, the cam bars will operate to unlock and lock the shafts. While the gears 30 50 rotate through 180° from the position shown in Figure 1, the cam cranks 53 will remain stationary; while the gears rotate through another 150°, the cam cranks 53 35 will rotate in a clockwise direction, causing the levers 55 to rotate in an anti-clockwise direction, shifting the shaft 105 horizontally toward the shaft 35 and compressing the springs 62; while the gears complete the 40 revolution, the compressed springs will cause the shaft 105 to shift back to the position shown in Figure 1, and swing the levers 53 and 55 back to the position shown in Figure 1.

45 While the shaft 35 is locked against rotation, the tank rises to immerse the female die or mold attached to the inverted die bracket (40 in Figure 1) and lowers to clear the die before the shaft 35 is rotated. For 50 every four revolutions of the gears 22, the shafts 35 and 105 will rotate one complete revolution, and for every revolution of said gears, a female die will be temporarily locked in a position to be immersed in the 55 liquid contained in the tank.

To each of the die brackets carried by the shaft 35 is detachably secured a female die, and to each of the brackets carried by the shaft 105 is secured the male die.

60 As the shafts 35 and 105 are momentarily locked against rotation, the shaft 105 is shifted horizontally toward the shaft 35, the male die engaging the corresponding female die to form the pulp article and to remove 65 same from the female die by suction.

The function of the vacuum chambers is to control the time at which each die is to be subjected to suction or is to be open to the atmosphere, the following being a detailed statement of the operation of each vacuum chamber and the control effected thereby.

As has been explained before, the castings 143 and 144 are locked against rotation while the shafts 35 and 105 rotate. When the die bracket 40 is in the position shown in Figure 75 1, the female die which it carries is in direct communication with the port 161 of the wax washer, and therefore operatively connected to the pipes 157 and 169 and to the vacuum tank 170 and pump 171. The suction created 80 by the pump 171 causes the water or solvent in the tank 12—the die 40 now being submerged—to flow through the laminations, through the pipe line in the shaft 35, and finally out of the pipe 169, a coating of the 85 pulp substance being deposited upon the laminations. The shaft 35 then rotates through an angle of 90°, the die bracket 40 moving to the position of the bracket 40A in Figure 1.

90 As the bracket 40 is rotating, it will remain operatively connected to the pump 171 until the die bracket pipe line has reached the end of the recess 163, after which the suction from said pump will be cut off. As 95 soon as the bracket has completed its rotation of 90°, the bracket 40 will become operatively connected to the port 161A, the pipes 157A and 166 and to the pump 167, the suction being here utilized to absorb the 100 moisture in the pulp substance deposited upon the laminations, or otherwise dry or drain said pulp. The bracket 40 is again rotated through 90° and comes to a stop in the position of bracket 40B in Figure 1. 105 The bracket 40 is operatively connected to the port 161B, to the pipes 157B and 166, and to the suction pump 167, the process of 110 drying the pulp substance on the laminations being continued. As soon as the bracket resumes its rotation to reach the position of bracket 40C in Figure 1, its communication with the pump 167 is cut off, and as soon as 115 it comes to a stop, it is operatively connected to the port 161C and the pipe 157C, and therefore open to the atmosphere.

120 While locked in this position, the shaft 105 moves horizontally toward the shaft 35, moving therewith the bracket 108B, now in the position of 108A in Figure 1, and causing the engagement of the male die carried by said bracket 108B with the female die carried by the bracket 40.

125 While the male die carried by the bracket 108B is in co-operative engagement with the corresponding female die, the said bracket is operatively connected to the port 161A of the wax washer carried by shaft 105, to the pipes 157A and 173 and the suction pump 174; the finished pulp article will therefore 130

be pulled out of the female die and into the male die. As the shaft 105 then shifts back to its normal position, the finished article is retained in the female die by suction.

5 The bracket 40 will then resume its rotation of 90° until it is back into the position shown in Figure 1. The bracket 100B then rotates through an angle of 90° until it reaches the position of 108 in Figure 1, and 10 while thus rotating, it will then become operatively connected with the recess 175 and therefore with the port 161B, the pipes 157B and 171, and the suction pump 172. The moisture or water in the article will still be 15 further dried up or absorbed. The bracket will next rotate through another angle of 90° to the position of bracket 108C in Figure 1, when it will become operatively connected to the port 161C and to the pipe 157C, 20 and therefore to the atmosphere. The bracket 108C is then rotated through another 90° to the position of bracket 108 in Figure 1, the bracket being open to the atmosphere.

25 The pulp article is now ready to fall off the female die, and a device or stripper is here used for this operation, any suitable device now known to the art being used.

What I claim is:

1. In a machine for molding pulp articles, 30 a mold, a tank adjacent said mold for immersing the mold into a liquid pulp mixture, suction-producing means operatively connected to said mold, and a conduit between said suction-producing means and said tank 35 for agitating the pulp mixture contained therein.

2. In a machine for molding pulp articles, 40 a member intermittently rotating in fixed bearings and having a plurality of spaced female dies therearound, means for immersing said dies in a liquid pulp mixture, a second member intermittently rotating in sliding bearings and moving forward toward and rearwardly away from said first-mentioned member, springs yieldingly resisting the forward movement of said second member, means for rotating said members, a plurality of spaced male dies carried by said second member and co-acting with said 50 female dies for finishing the pulp articles, suction-producing means operatively connected to said dies, and automatic means of controlling said suction-producing means so as to transfer the pulp articles from said 55 female dies on to said male dies and subsequently releasing same.

3. In a machine for molding pulp articles, 60 a frame, a shaft rotatable in fixed bearings, a second shaft rotatable in sliding bearings and in parallel arrangement with said first-mentioned shaft, die brackets carried by said shafts at regular intervals therealong, indexing plates rigidly carried by said shafts and having notches in the periphery thereof, indexing fingers co-acting with the

notches in said indexing plates for locking said plates against rotation, a pair of gears each carrying a dog therewith, means for actuating said gears, and a lever mechanism operated by said dogs for disengaging said 70 fingers from said notches.

4. In a machine for molding pulp articles, 75 a frame, a shaft rotatable in fixed bearings, a second shaft rotatable in sliding bearings and in parallel arrangement with said first-mentioned shaft, die brackets carried by said shafts at regular intervals therealong, a pair of gears rotatably mounted under said first-mentioned shaft and each carrying a cam in the axis thereof, a pair of arms 80 pivotally mounted on said frame and having the upper end thereof slotted to slidably and rotatably engage the end of said second-mentioned shaft, means co-acting with said cams for oscillating said arms, and means for 85 actuating said gears.

5. In a machine for molding pulp articles, 90 a rotatable shaft mounting a plurality of evenly spaced die brackets, a non-rotatable casting on one end of said shaft forming therewith a chamber, a pipe line operatively connecting each of said die brackets to said chamber, a non-rotatable disc in said chamber having ports spaced to co-act with said pipe lines, a second disc in said chamber 95 spring held against said first-mentioned disc and carrying pipes therewith spaced to be in alignment with said ports, and suction-producing means operatively connected to a 100 number of said last-mentioned pipes.

6. In a machine for molding pulp articles, 105 a frame, a shaft rotatable in fixed bearings, a second shaft rotatable in sliding bearings and in parallel arrangement with said first-mentioned shaft, a ratchet plate rigidly carried by each of said shafts, a disc loosely mounted on each of said shafts and having a pawl co-acting with said ratchet, links and a lever therebetween adapted to rotate said 110 discs simultaneously in a same direction, means for oscillating said lever from the rotation of the drive shaft of said machine, and means for periodically shifting said last-mentioned shaft from the rotation of 115 said drive shaft.

7. In a machine for molding pulp articles, 120 a member rotating on a horizontal axis and having a plurality of spaced dies, a tank slidably mounted under said member and rising to immerse said dies and lowering to clear said dies, suction-producing means operatively connected to said dies, and means co-acting with said dies for removing the pulp articles.

8. In a machine for molding pulp articles, 125 a rotatory member having a plurality of dies therearound, a drive shaft, means adapted for driving said rotatory member from the rotation of said drive shaft, a tank slidably mounted under said rotatory member, and 130

means adapted for raising and lowering said tank from the rotation of said drive shaft.

9. In a machine for molding pulp articles, a rotatory member having a plurality of dies therearound, a drive shaft, means for driving said rotatory member from the rotation of said drive shaft, a tank slidably mounted under said rotatory member and having pivot bearings, eccentrics rigid on said drive shaft 10 below said pivot bearings, and eccentric rods connected between said pivot bearings and eccentrics.

10. In a machine for molding pulp articles, a rotatory member having dies spaced therearound, means for successively immersing said dies into a liquid pulp mixture and depositing a layer of pulp upon said dies, a second rotatory member having dies spaced therearound and formed to 20 act with said first-mentioned dies in removing the pulp articles, means for rotating said rotatory members simultaneously with rest periods therebetween, means for shifting said second rotatory member toward said

first-mentioned rotatory member to cause the engagement of corresponding dies, and suction means for transferring the pulp articles from dies in one member to the corresponding dies in the other member by succession.

11. In a machine for molding pulp articles, a rotatory member having dies spaced therearound, means for successively immersing said dies into a liquid pulp mixture and depositing a layer of pulp upon 35 said dies, a second rotatory member having dies spaced therearound and formed to engage with said first-mentioned dies and finish the pulp articles, means for shifting said second-mentioned member towards said first-mentioned member to cause the engagement of corresponding dies in said rotatory members, and means for adjusting the initial resting position of said second rotatory member.

Signed at the city of Toronto, this 4th day of December, 1926.

JAMES FLEMING LOW.
